UNITED STATES PATENT OFFICE.

LEON J. HECHT, OF INDIANAPOLIS, INDIANA, ASSIGNOR TO SMITH-HECHT COMPANY,
OF INDIANAPOLIS, INDIANA, A PARTNERSHIP.

FOLDING CARDBOARD FAN.

Application filed October 31, 1921. Serial No. 511,889.

To all whom it may concern:

Be it known that I, LEON J. HECHT, a citizen of the United States, and a resident of Indianapolis, county of Marion and State 5 of Indiana, have invented a certain new and useful Folding Cardboard Fan; and I do hereby declare that the following is a full, clear, and exact description thereof, reference being had to the accompanying drawings, in which like numerals refer to like parts.

This invention relates to a fan construction and the chief object thereof is to so construct a fan that the parts thereof may 15 be folded in such a manner that the fan may be carried in a pocket when folded, yet be of sufficient area for fanning purposes when unfolded. The aforesaid object has been accomplished by the ordinary fan 20 known as the Japanese fan, but the cost of such a fan is prohibitive for certain purposes and the chief feature of this invention is to construct a folding fan of relatively cheap material in the suggested manner, yet provide a relatively endurable construction.

Another feature of the invention consists in the provision of means for reenforcing the handle or grasping portion of the fan 30 which reenforcement likewise reenforces the fan construction when in folded relation to prevent breakage or bending thereof at the weakest point.

The full nature of this invention will be 35 understood from the accompanying drawings and the following description and claims.

In the drawings Fig. 1 is a plan view of blank from which a one piece folding fan is 40 formed. Fig. 2 is a similar view showing the fan in the folded relation.

In the drawings 10 indicates a suitable blank which herein is illustrated as a one piece construction provided with an arcuate outer edge and radial edges. The fan 45 comprises a plurality of sections and herein 11 indicates an intermediate and central section and 12 indicates a pair of substantially sectored end sections. The sections 50 11 and 12 are flexibly connected together and herein such flexible connection is formed by scoring the blank at 13 and 14. These scorings, as will be noted, are radially positioned upon the blank. The ma-

terial comprising the blank is preferably 55 card board or a similar relatively stiff substance, but other equivalent material may be used without departing from the invention.

The blank is also provided with end flaps 60 15. An end flap 15 is flexibly connected to an end section 12 and herein such flexible connection is formed by scoring the blank at 16 and such scoring is the reverse from that indicated at 13 and 14, so that the reenforcing or laterally extending sections 15 may be folded back upon the section 12 and be rigidly secured thereto in any suitable manner such as by application of adhesive. Herein three sectored sections are illustrated, the intermediate section 11 including a greater central angle than the end sections 12. Since the blank is scored to flexibly connect the sections 12 to the sections 11 in the manner indicated, said end sections 20 are foldable over and upon the intermediate section 11, such that one end section is foldable within the intermediate section 11 and the other end section 12.

When the sections of the fan are in folded 80 relation, the reenforcing sections 15 reenforce the central portion of the sectored sections, making a total, as illustrated in the present invention, of five thicknesses for a triple section fan.

It will be noted that the aforesaid fan construction can be very cheaply constructed from a one piece card board blank or the like and said fan has the additional advantage of being foldable into compact 90 form so as to be receivable by the pocket for transporting purposes and likewise said construction provides a free face adapted to receive advertising media or the like and the sections when in folded relation protect 95 said advertising media or information from casual injury or obliteration.

The invention claimed is:

1. A folding fan comprising a single piece of cardboard scored in a plurality of places 100 upon one side to provide a plurality of sections foldable one within the other, and reversely scored to provide a reenforcing section at the grasping portion of the fan.
2. A folding fan comprising a single piece 105 of card board or similar material scored upon one side in a plurality of places to provide a plurality of sections foldable one

within the other and reversely scored at opposite ends of the base to provide a pair of reenforcing end sections at the grasping portion of the fan.

5. 3. A one piece folding fan comprising a single piece of card board or similar material radially scored in a plurality of places

upon one face and reversely and radially scored at the ends of the piece to provide a reenforcing flap at opposite ends at the 10 grasping portion of the fan.

In witness whereof, I have hereunto affixed my signature.

LEON J. HECHT.
